BUBBLE-BLOWING TOY

Harold D. Versten, Chicago, Ill., assignor to Chemtoy Corporation, Cicero, Ill.

Filed Nov. 11, 1974, Ser. No. 522,429

Term of patent 7 years

Int. Cl. D21—01

U.S. Cl. D34—15 H

FIG. 1

FIG. 2

FIG. 3

FIG. 5

FIG. 4

FIG. 1 is a top plan view of a bubble-blowing toy showing my new design;

FIG. 2 is a rear elevational view thereof;

FIG. 3 is a side elevational view thereof, the side opposite being a mirror image;

FIG. 4 is a front elevational view thereof; and

FIG. 5 is a bottom plan view thereof.

I claim:

The ornamental design for a bubble-blowing toy, as shown and described.
